UNITED STATES PATENT OFFICE

155,108

DESIGN FOR A PEDICURE INSTRUMENT

Leslie C. Rucker, Arlington, Va.

Application October 22, 1947, Serial No. 142,085

Term of patent 14 years

(Cl. D86—10)

To all whom it may concern:

Be it known that I, Leslie C. Rucker, a citizen of the United States, residing at Arlington, in the county of Arlington and State of Virginia, have invented a new, original, and ornamental Design for a Pedicure Instrument, of which the following is a specification, reference being had to the accompanying drawing, forming a part thereof.

Fig. 1 is an enlarged fragmentary perspective view of an end of a pedicure instrument embodying my new design;

Fig. 2 is a top plan view of the pedicure instrument;

Fig. 3 is a side elevational view thereof; and
Fig. 4 is an end view thereof.

The dominant feature of my design for a pedicure instrument resides in the portion shown in full lines.

I claim:

The ornamental design for a pedicure instrument, as shown and described.

LESLIE C. RUCKER.
